UNITED STATES PATENT OFFICE.

EDWIN R. F. HART, OF CHICAGO, ILLINOIS.

DESIGN FOR A FRAME FOR WASHING-MACHINES.

SPECIFICATION forming part of Design No. 26,993, dated April 27, 1897.

Application filed November 30, 1896. Serial No. 614,005. Term of patent 14 years.

To all whom it may concern:

Be it known that I, EDWIN R. F. HART, a citizen of the United States of America, residing at Chicago, in the county of Cook and State of Illinois, have invented and produced a new and original Design for Frames for Washing-Machines, of which the following is a specification.

My invention relates to a new and useful design for a washing-machine frame, the invention consisting in a new and useful configuration of such frame, which will be fully described below and the essential features thereof pointed out.

15 The drawing shows my design by means of a perspective view of the complete frame as the same appears from the rear and right-hand side thereof.

20 The frame has two horizontal feet A B, rectangular in cross-section, having flat undersides and tops tapering from their middle portions downward in opposite directions. From the middle of each of the feet rises an upright portion of the frame C D, largest at its bottom and tapering toward the top, but enlarged at the extreme top at E F. A horizontal portion of the frame G, rectangular in cross-section and of much greater width than thickness, connects the top portions of the

uprights, the width of said portion G being 30 arranged vertically. From said portion G two vertical portions of the frame H I extend downward from points at substantially the same distance inward from the respective uprights C D, the portions H I being also rectangular 35 in cross-section. At the bottom said portions H I are connected by a second horizontal portion J, rectangular in cross-section, of considerable width as compared with its thickness, and also arranged with said wider dimension in a vertical line. The portion J is 40 perforated in oblique lines.

The essential features of my design I consider to be the rectangular cross-section of the various parts, the tapering of the feet A B 45 in opposite directions from their middle portions, the tapering of the uprights C D in an upward direction, and the enlargement of said uprights at the top.

I claim as new and desire to secure by Letters Patent—

The design for a washing-machine frame herein shown and described.

EDWIN R. F. HART.
